HAIR ORNAMENT OR SIMILAR ARTICLE

Myron Heifetz, Jackson Heights, N.Y. (½ Flower Style Originals, 15 E. 31st St., New York, N.Y. 10016)

Filed Oct. 13, 1964, Ser. No. 82,161

Term of patent 14 years

(Cl. D86—10)

FIG. 1

FIG. 3

FIG. 1 is a top edge view of a hair ornament or similar article embodying my new design;

FIG. 2 is a front view thereof; and

FIG. 3 is a cross-sectional view taken on line 3—3 of FIG. 2.

This application is a continuation-in-part of my co-pending application Serial No. D.78,681 filed February 18, 1964 and now abandoned.

I claim:

The ornamental design for a hair ornament or similar article, substantially as shown and described.
